William C. Rogers, 5365 NW. 36th St.,
Miami Springs, Fla.

Filed Apr. 6, 1961, Ser. No. 64,644

Term of patent 14 years

(Cl. D26—14)

FIGURE 1 is a perspective view illustrating one end and the side of an aircraft antenna T-fitting or similar article, embodying my new design,

FIGURE 2 is a side elevational view thereof,

FIGURE 3 is an end elevational view thereof, and

FIGURE 4 is a bottom plan view thereof.

The drawing figures are shaded to indicate contrast in appearance between the threaded, tapered caps and the separable halves of the wire-joint insulator.

I claim:

The ornamental design for an aircraft antenna T-fitting or similar article, as shown and described.
